(57) **CLAIM**

The ornamental design for a pole lamp, as shown and described.

DESCRIPTION

FIG. 1 is a perspective view of a pole lamp according to my new design;

FIG. 2 is a top plan view of the lamp of FIG. 1 on an enlarged scale;

FIG. 3 is a front elevational view of the lamp of FIG. 1;
FIG. 4 is a right side elevational view of the lamp of FIG. 1, the left side being a mirror image; and,
FIG. 5 is a rear elevational view of the lamp of FIG. 1.
